UNITED STATES PATENT OFFICE.

WILLIAM H. DOWE, OF NEW YORK, N. Y., ASSIGNOR TO CINCHA
STOPPER COMPANY, A CORPORATION OF MAINE.

BOTTLE-STOPPER.

No. 832,728.

Specification of Letters Patent.

Patented Oct. 9, 1906.

Application filed January 18, 1906. Serial No. 296,789.

To all whom it may concern:

Be it known that I, WILLIAM H. DOWE, a citizen of the United States, residing at the city of New York, in the borough of Brooklyn and State of New York, have invented 5 certain new and useful Improvements in Bottle-Stoppers, of which the following is a full, clear, and exact description.

My invention relates to bottle-caps, and 10 has for its principal object to provide a cap of cheap construction and capable of sealing a bottle efficiently and which is easily removable by the purchaser without requiring any special tools or difficult manipulation.

15 With this object in view my invention consists in the construction of cap hereinafter set forth and shown and finally particularly pointed out in the appended claim.

In the drawings, Figure 1 is a perspective 20 view of a cap embodying the principles of my invention. Fig. 2 is a sectional view of the same applied to a bottle. Fig. 3 is a side view.

Bottle-caps are now produced and are in 25 common use which are sufficiently cheap and efficient for sealing a receptacle; but so far as I am aware, none of the forms having sufficient cheapness and practical efficiency in sealing a bottle have been removable with- 30 out special tools or manipulating a plurality of different parts or elements thereon. In other words, the desideratum of a cap which will efficiently seal a bottle, but which is removable by merely opening a single tag with 35 the fingers, has not yet been attained. In carrying out the present invention I aim to provide a cap of this character.

Referring to the drawings, in which like 40 parts are designated by the same reference-sign, 1 denotes a cap of sheet metal or other suitable material having a top plate 2 and a circumferential depending rim 3 stamped or formed thereon.

45 4 indicates depending tags or fingers upon the rim, each of which is embossed or beaded at 5, so as to engage the bottle-neck, and has a lower extending part or extremity 6, which serves as an engaging-point for the fingers when it is desired to remove the cap from the 50 bottle.

7 denotes the usual packing or sealing disk of cork or analogous material.

The beads 5 are preferably embossed directly upon the material of the depending

tags or fingers and do not extend wholly 55 across the width thereof. In this way the beads serve a double function—namely, to form shoulders for engagement with the bottle-neck and as stiffening-ribs for the fingers themselves for a purpose which will later appear. The rim 3 is undercut or notched, as shown at 8, adjacent to the depending tags or fingers 4, by which the tags or fingers have a greater effective length than would be the case if they extended directly from the lower 65 edge of the rim. I arrange the depending fingers 4 in a special way, which constitutes a very important feature of my invention.

Each of the tags or fingers depends from the cap at a point exactly one hundred and 70 twenty degrees from the others. In other words, the three fingers are triangularly related to one another, and in this way it is possible to clamp the cap upon the bottle with the necessary practical efficiency and yet 75 enable its removal by the bending of a single finger.

The use of the invention is as follows: The cap, being placed upon a bottle, is clamped into sealing relation in the usual way by pressing inward the various depending tags or fingers, so that their beaded portions 5 engage the usual inclined wall A, Fig. 2, of the bottle and draw the cap downward thereon. In this way the cap is placed in sealing relation 80 on the bottle and remains so as long as desired. This is by reason of the symmetrical character of the drawing forces produced by the three tags or fingers. Bottle-necks are in practice more or less irregular, and it is absolutely essential to have at least three points 85 of drawing engagement in order to enable the cap to be properly borne down thereon. At the same time the arrangement of three equally-spaced tags or fingers permits the 90 removal of the cap by bending any one of them, since the remaining two are not sufficiently spaced apart to hold the cap upon the bottle if any one of the tags is bent or broken.

When, therefore, it is desired to open the bottle, it is merely necessary to pry one of the tags laterally with the fingers or thumb-nail, by which it is bent at its point of junction with the rim. The stiffening action of the bead 5 is important in this connection in that it insures the opening of the tag or finger at the point required and not at a point in the line of the bead. If, however, the tag should fail 100 105

to bend at the proper point or should not wholly release the cap, it is possible to repeat the process with another finger or tag until all of the three have been bent. Under ordinary circumstances the cap is releasable by the single finger or tag initially bent.

What I claim is—

A bottle-cap comprising a top plate having a circumferential depending rim, three tags or fingers depending from said rim and equally spaced at distances of one hundred and twenty degrees thereabout, beads embossed upon said tags or fingers to extend partly across the width thereof and adapted 15 to engage the usual inclined wall of a bottle-

neck, said fingers having terminal portions or extremities slightly deflected outward from the plane of the finger to produce an engagement-point for the operator's fingers, said rim being notched around its circumference at points adjacent to and on either side of the respective tags or fingers, substantially as described.

In witness whereof I subscribe my signature in the presence of two witnesses.

WILLIAM H. DOWE.
